CLAIM

The ornamental design for a filter, as shown and described.

DESCRIPTION

FIG. 1 is a front perspective view of the present invention;
 FIG. 2 is a front elevation view of the present invention;
 FIG. 3 is a rear elevation view of the present invention;
 FIG. 4 is a right side view of the present invention;
 FIG. 5 is a left side view of the present invention;
 FIG. 6 is a top view of the present invention; and,
 FIG. 7 is a bottom view of the present invention.
